US00D931012S

(12) **United States Design Patent** (10) **Patent No.:** **US D931,012 S**
Ouyang (45) **Date of Patent:** **** Sep. 21, 2021**

(54) **PILLOW**

(71) Applicant: **Shenzhen Damuzhi Health Information Consulting Co., Ltd.**, Shenzhen (CN)

(72) Inventor: **Xiaoling Ouyang**, Jiangxi (CN)

(73) Assignee: **Shenzhen Damuzhi Health Information Consulting Co.**, Shenzhen (CN)

(**) Term: **15 Years**

(21) Appl. No.: **29/753,787**

(22) Filed: **Oct. 1, 2020**

(51) **LOC (13) Cl.** **06-09**

(52) **U.S. Cl.** USPC **D6/601**

(58) **Field of Classification Search**
